ELECTRON-BEAM GUN

Charles R. Kelly, Pittsburgh, Pa., assignor to United States Steel Corporation, a corporation of Delaware
Filed Oct. 5, 1965, Ser. No. 493,154
3 Claims. (Cl. 313—279)

ABSTRACT OF THE DISCLOSURE

An electron-beam gun including a thermionic emitter is provided with a trough-shaped baffle confining electron emission to a limited arc outwardly from the emitter. The baffle is of hour-glass shape longitudinally, i.e., has its mid-portion drawn in to a width less than that of the end portions. This tends to correct non-uniform emission along the length of the emitter by reducing emission in the region where it would be greatest, without the use of the invention.

This invention relates to electron-beam guns and, in particular, to an elongated gun having provision for achieving a more uniform bombardment of the mass to be heated, along the length of the gun, than has been obtainable heretofore.

Electron-beam guns are now extensively used, principally for heating material in vacuum processes. In fact, industrial operations now contemplated require the heating of material over a width of several feet, i.e. metal strip or the surface of a mass of molten metal to be vaporized. This necessitates elongated guns and, indeed, the end-to-end assembly of a plurality of guns. An elongated gun with a straight tungsten wire as the thermionic electron emitter has the shortcoming that the density of electrons emitted increases from both ends toward the center because of the cooling effect of the support means and current-supply connections. As a result, the density of the electron-beam delivered and the heating effect thereof, vary considerably across the width of the material or mass to be heated. It is therefore the object of my invention to provide an electron-beam gun capable of delivering a beam of electrons which produces a heating effect with less variation longitudinally of the emitter.

In a preferred practice of my invention, I provide a trough-shaped backing electrode or shield for the hot-wire emitter, which has a pinched-in or necked-down central portion. This portion tends to restrict the escape of electrons from the mid-portion of the emitter and causes the build-up of a cloud of electrons forming a space charge which itself reduces the discharge of electrons from the mid-portion of the emitter. The overall result is that there is less difference between the heating effect on the work (metal strip or evaporand) between the middle and ends of the gun than has been encountered using guns available heretofore.

A complete understanding of the invention may be obtained from the following detailed description and explanation which refer to the accompanying drawings illustrating the present preferred embodiment. In the drawings:

FIGURE 1 is a plan view with a part broken away;

FIGURE 2 is a longitudinal section taken along the plane of line II—II of FIGURE 1, with a part broken away; and

FIGURE 3 is a transverse section taken along the plane of line III—III of FIGURE 1.

Referring now in detail to the drawing, the gun of my invention is mounted on a base 10 between upstanding

2

side walls 11. The ends are open so the guns may be assembled end-to-end in multiple-unit relation. The elongate character of the gun is apparent from FIGURE 1. The base and side walls are at ground potential as is also a sheet-metal accelerating anode 12 carried on the side walls and extending therebetween. Anode 12 has an opening or window 13 therein.

A high-voltage (negative) platform 14 is mounted on insulators 15 upstanding on base 10. Insulators 16 are mounted in pairs on platform 14 adjacent the ends thereof. Cross bars 17 of conducting metal join the insulators of each pair. Terminal clips 18 are secured, in aligned relation, to the bars 17 and a length of tungsten wire 19, the electron emitter, extends between them. Current-supply conductors (not shown) are connected to the bars 17 and extend to a source of emitter-heating current.

Angle brackets 20 secured to platform 14 support a trough-shaped open-ended backing electrode or shield 21 partially enclosing emitter 19. The side walls of the shield are pinched in or necked-down at the mid-portion as indicated at 22. The effect of this shape is to restrict somewhat the outflow of electrons from the emitter at its mid-portion, compared with the outflow adjacent the ends thereof. As shown in FIGURE 1, the shape of opening 13 approximates that of shield 21, being slightly larger than the latter overall.

As previously pointed out, the necked-in mid-portion 22 of shield 21 narrows the exit for electrons passing from emitter 19 to the anode (mass to be heated), not shown. Thus the resultant heating effect of the electron beam is applied to an area on the mass to be heated opposite the middle of the gun, narrower than the areas opposite the ends of the emitter. This tends to smooth out the difference otherwise existing between the heating effect of the beam at various points along the length of the region of impingement.

Although I have disclosed herein the preferred embodiment of my invention, I tend to cover as well any change or modification therein which may be made without departing from the spirit and scope of the invention as set forth in the claims.

I claim:

1. An electron-beam gun comprising a support, terminals mounted thereon in spaced relation, an electron emitter wire extending between terminals, and a trough-shaped backing electrode mounted on the support between it and the wire, the sides of said electrode being pinched in toward each other adjacent the mid-portion of the wire.
2. An apparatus as defined in claim 1, characterized by an accelerating anode sheet overlying said backing electrode and having an opening therein conforming in shape to that of said electrode in plan.
3. An apparatus as defined in claim 1, characterized by said support being a platform, a base having insulators thereon carrying said platform, side walls extending upwardly from said base, and an accelerating anode sheet extending between said side walls.
